US0D1103744S

(12) **United States Design Patent** (10) **Patent No.:** **US D1,103,744 S**
(45) **Date of Patent:** **** Dec. 2, 2025**

(54) **RETAINER MEMBER**

(71) Applicant: **Independence Materials Group, LLC**,
Virginia Beach, VA (US)

(72) Inventor: **William A. Gantt**, Blair, SC (US)

(73) Assignee: **Independence Materials Group, LLC**,
Virginia Beach, VA (US)

(**) Term: **15 Years**

(21) Appl. No.: **29/823,169**

(22) Filed: **Jan. 14, 2022**

(51) LOC (15) Cl. **08-05**

(52) U.S. Cl.

USPC **D8/354**

(58) **Field of Classification Search**

(57) **CLAIM**

The ornamental design for a retainer member, as shown and described.

DESCRIPTION

FIG. 1 is a perspective view of a retainer member showing my new design;

FIG. 2 is a front view of the retainer member of FIG. 1;
FIG. 3 is a rear view of the retainer member of FIG. 1;
FIG. 4 is a first side view of the retainer member of FIG. 1;
FIG. 5 is a second side view of the retainer member of FIG. 1;

FIG. 6 is a top view of the retainer member of FIG. 1;
FIG. 7 is a bottom view of the retainer member of FIG. 1;
and,

FIG. 8 is a perspective view of the retainer member of FIG. 1 in an environment in which a wall support member is installed to the retainer member.

The broken lines in FIGS. 1-7 depict portions of the retainer member that form no part of the claimed design. The additional broken lines shown in FIG. 8 depict environmental subject matter and form no part of the claimed design.

1 Claim, 6 Drawing Sheets
